UNITED STATES PATENT OFFICE.

CHARLES HERBERT SCOTT, OF GLOUCESTER, ENGLAND; WALTER SCOTT, OF MANCHESTER, ENGLAND, WALTER SCOTT, OF SHIPLEY, ENGLAND, AND JOHN EDWARD WESTLE, OF GLOUCESTER, ENGLAND, EXECUTORS OF SAID CHARLES HERBERT SCOTT, DECEASED.

MACHINE FOR PRINTING LINOLEUM, FLOOR-CLOTH, AND THE LIKE.

1,323,107.

Specification of Letters Patent.

Patented Nov. 25, 1919.

Application filed March 9, 1918. Serial No. 221,485.

To all whom it may concern:

Be it known that I, CHARLES HERBERT SCOTT, a subject of the King of Great Britain, residing in Gloucester, England, have 5 invented certain new and useful Improvements in Machines for Printing Linoleum, Floor-Cloth, and the like, of which the following is a specification.

This invention relates to machines for 10 printing floor-cloth, linoleum and the like, of the type which comprises a convenient frame fitted with a bed over which the material to be printed is traversed in an intermittent or step-by-step manner by any suitable 15 means such as an endless band to which intermittent motion is imparted in any appropriate way and which is provided with spikes or other gripping means to hold and move the material to be printed, and in 20 which the printing blocks for the different colors are arranged in sequence above the bed or table and spaced at suitable distances apart, preferably at two or three times the 25 length of the repeat of the pattern to be printed, each printing block being fitted to a transverse beam which is given an up and down motion from suitable mechanism, and the colors applied to the blocks by suitable 30 devices which may be of known character and comprise each a tiering roller mounted in a color or tiering box and which are traversed underneath the blocks and deposit color upon their surfaces at the time when the printing mechanism is at rest.

35 The main motions of such a block printing machine are three:—

(a) The movement up and down of the printing blocks;

(b) The movement backward and forward of the tiering or coloring rolls or other tiering devices; and

(c) The movement for feeding forward the material which occurs about the same time as the movement of the tiering devices.

45 Up to the present, it has been customary to drive such machines from a rotary shaft by transferring the rotary movements into rectilinear movements through mechanism such as cams or similar devices and as it is 50 difficult to construct such mechanism to operate smoothly and without jerks, the speed at which such machines can be run has been limited. One reason for this limitation is

that beyond a certain limit there is a danger of the coloring material being thrown about 55 and so spoiling the fabric being printed. Such mechanism is also complicated and expensive.

The present invention consists in improvements designed to simplify and cheapen the 60 construction of the above type of machines and generally to improve their working.

A main object of the improvements is to provide driving means which shall operate smoothly and without jerks and permit of a 65 machine of the above type being operated at a higher speed than heretofore and thus give a greater output of printed material.

One of the improvements consists in employing, a fluid pressure driving mechanism 70 to operate the various movements of the machine. Other improvements comprise certain modifications of the construction of parts of the improved machine as will be hereinafter described.

75 In carrying out the invention I employ one or more hydraulic cylinders which are adapted to act upon the reciprocating parts of the machine to produce the necessary movements thereof. I, preferably, employ 80 two such cylinders or sets of cylinders adapted to operate alternately, one to actuate the printing blocks and the other to actuate the tiering devices and to feed forward the material. It is obvious that to prevent collision between the printing blocks and the tiering devices, these must not both be moved at the same time, and for this purpose I use a valve system which will prevent 85 one cylinder coming into operation until the other has completed, or nearly completed, its traverse. I may, for instance, operate the valve of one cylinder by the movement of the piston in the other cylinder in the manner known in connection with duplex 90 pumps.

I will further describe my invention with reference to the accompanying drawings, in which:—

Figure 1 is a diagrammatic side view 100 showing some parts of a machine constructed according to this invention, the printing blocks being shown in the elevated position or the position of rest.

Fig. 2 is a side elevation to an enlarged 105 scale of a portion of the machine which is

shown diagrammatically in Fig. 1, three printing blocks, three tiering devices and a part of the mechanism for feeding the material intermittently being included.

5 Fig. 3 is a cross section of the machine, parts being omitted.

Fig. 4 is a side view of a pair of fluid pressure cylinders shown in Figs. 1 and 3 and their valve-controlling gear.

10 Fig. 5 is a plan illustrating valve controlling gear and one arrangement of a differential motion for controlling the valves of two fluid pressure cylinders corresponding to those shown in Figs. 1 and 3.

15 Fig. 6 is a cross section on line 6—6 in Fig. 5.

Figs. 7 and 8 are two views illustrating a throttle valve-controlling device.

20 Fig. 9 is a fragmentary plan view showing a portion of the piston cylinder depicted in Fig. 5 having applied to it the controlling device illustrated in Figs. 7 and 8.

In the several figures the corresponding parts are indicated by the same letters.

25 The linoleum printing machine frame, printing blocks and color boxes may be of any suitable construction, but the following is a description of a convenient arrangement thereof.

30 The side framing of the machine consists of a bottom member A and top member B, Figs. 2 and 3, the latter member having facings on the bottom and sides for carrying sliding bars C and vertical slides D forming part of the printing motion, and facings on the top to carry the racks E forming part of the mechanism for revolving the tiering roller W'. Brackets G are fixed at intervals to the inside of the members B to 40 carry guides H for the bands F for forwarding the material I and also plates J for carrying the impression pad K. The bottom members A may be of angle section and be suitably connected as for instance by 45 cross lattice girders L. Some of the cross members L may be fitted with pedestals M for holding the shafts N of the wheels O on which the machine can be traversed.

At each end of the side frames are fitted 50 bearings for carrying the shafts P of the drums Q for forwarding the material, of which drums one only is shown in Fig. 2.

The printing blocks R are mounted by means of suitable traverses to two cross members R', which are joined together at each end by castings or members R² which form the trunnions by means of which the blocks R can be turned over when desired.

55 The vertical slides D may be constructed of cast iron or other suitable substance with a bearing D' at the top to carry the trunnions R². They work on guide brackets S fixed to the top and bottom members A and B. The slides are united at the bottom end 60 by a shaft T that is furnished with two

eccentrics T'. Each end of shaft T is fitted in a slide block adjustable by means of raising and lowering screws T² so that the initial or normal position of the printing block can be raised or lowered as desired. 70 The toggle rods U are fitted on to the eccentrics T' and one outer end of the shaft T is fitted with a handle T³ and stop catch T⁴ so that it can be revolved half a circle, the throw of the eccentrics being such as to 75 raise the block sufficiently to put it out of action. The printing block R at the right hand end of Fig. 2 is shown in such out of action position.

The printing motion may, as shown, consist of the flat horizontal slide bars C, on each side of the machine. Each pair of these bars is fitted with cast iron cross-heads C', one for each printing block bolted between the bars and working in guideways 85 on the lower face of the top member B. The crossheads are furnished each with a joint C² for the upper end of a toggle rod U, the lower end of the rod being on the eccentric T' of the corresponding cross shaft T as 90 before mentioned. These bars C when operated as described below travel backward and forward in a horizontal plane and by means of the toggle rods U give a vertical motion to the slides D carrying the printing blocks. 95 The weight of these side bars C can be carried on a series of rollers V provided with ball bearings and supported from the framing. The pin V' on which this roller runs is made eccentric so that the height of the 100 roller can be adjusted as desired.

The tiering devices comprise a color box W and a roller W' for applying color to the printing block, mounted therein. There

are as many of these devices as there are 105 printing blocks. The ends of the boxes are mounted on angle bars W² extending the whole length of the machine and adapted to

110 run on rollers W⁴ mounted on the members B. The angle bars W² are each fitted with pieces or brackets W⁵ projecting below the

table of the machine, arranged so that they go down between the top member of the

members B and the band guides H, the brackets G that carry the band guides being

arranged so as to allow room for the travel of the color boxes. The lower end of

115 brackets W⁵ are secured by means of a cross-head Y² to the piston rod Y' of a fluid pressure or hydraulic piston cylinder Y placed

on the center line of the machine and employed for reciprocating the tiering devices.

A similar cylinder Z is placed below piston

120 cylinder Y, the piston rod Z' of which is secured to the bars C for driving the print-

125 motion by a cross-head Z².

In Fig. 1 and also in Figs. 2 and 3 the bars C and toggle rods U are shown in the 130 positions they have initially or prior to the printing operation. As the piston of cylin-

der Z moves outwardly so that the bars make a forward stroke in the direction of the arrow X in Fig. 1, each rod U will turn about its pivotal connections until it assumes a position on the other or left side of slide D and inclined to the slide at an angle equal to that which the rod makes with the slide when in the initial or right hand position. These movements of rods D cause the respective printing blocks R first to move down and then up during the said forward stroke.

Blocks R will make corresponding movements while bars C make the return or rearward stroke. The tiering devices prior to a printing operation occupy positions between the printing blocks R. Other suitable mechanism for operating the printing blocks and tiering devices from the cylinders may be alternatively employed.

Fig. 4 shows one way in which the movement of the piston of one of the cylinders Y, Z may be arranged to control the valve system of the other cylinder. Respectively associated with cylinders Y and Z are valve boxes y and z and valve rods y', z', the latter being provided with extension or connecting rods y², z². It will be seen from Fig. 4 that an arm a fixed to piston rod Y' of cylinder Y will in its reciprocating movements engage alternately with stops b and b' secured to the knock or tappet rod z² of cylinder Z, thereby reciprocating the valve rod z' and controlling the valve system of cylinder Z. The arm a may be carried by or be a part of the framed cross-head X referred to above. An arm c on piston rod Z' of cylinder Z is adapted, as the piston rod moves to and fro, to engage alternately stops d and d' on a knock or tappet rod e which is mounted to slide in suitable bearings (not shown) and is at one extremity pivotally connected to one end of a lever f which is suitably pivoted at f' between its ends and at its other end pivotally connected by means of the rod y² to the valve rod y'. It is clear that the valve rod y' will by the action of the parts d, d', f and y² be reciprocated as the piston rod Z' moves to and fro, the valve system in valve box y being accordingly controlled.

To regulate the speed during the strokes of the pistons I prefer to fit the cylinders with differential motions which may be of any suitable known kind and by means of which each cylinder gradually closes its own valve as it moves, the amount of such closure being adjustable at will.

Each of such motions or gears would be operatively connected with the piston rod cross head of a cylinder and also with the valve rod of the valve in the valve box associated with that cylinder, so that as the piston rod moves and approaches the end of a stroke the differential gear will operate in a manner to cause the said valve to move

gradually toward one or other of its closed positions. Such gears would preferably be adjustable so that the periods at which closure of the corresponding valve is effected may be regulated.

In Figs. 5 and 6 is shown an arrangement wherein the movement of the piston of one cylinder controls the valve system of another or second cylinder and wherein is included a differential gear that is connected both with the valve system and with the piston cross-head of the said second cylinder. In these figures the valve boxes y and z attached respectively to the cylinders Y and Z, are shown arranged one on one side of the cylinders and the other on the opposite side. The means whereby the valve rod y' is operated by the movements of the piston rod of cylinder Z comprise a knock rod g carrying yielding or spring stops g', g² and g³ adapted to be operated by a part carried by the cross head Z² of the lower or printing cylinder Z. The rod g in its movements actuates the valve in valve box y by means of its connection to one end of a lever h pivotally connected between its ends to valve rod y'. The lever h is also operatively connected with the differential gear comprising the parts mentioned below. For this purpose the lever h at its other end is pivotally connected to one end of a rod i that forms part of the differential gear and is at its other extremity attached to a sleeve or bar j adjustably mounted on a radius rod k that is adapted to be turned about a fixed pivot l during the reciprocating movements of the cross head X by means of the rod m attached to that cross head. The said parts i, j, k, l, and m constitute the said differential gear.

If the point of attachment of rod i to sleeve j coincides with the pivot l, the valve in valve box y will be controlled entirely by the knock rod g. If, however, the point of attachment is moved away from pivot l to, say, a position as shown in Fig. 5, then the parts i, h and m will take part in regulating the movements of the valve.

A similar differential gear may be used in conjunction with the cross head Z² and the valve rod in valve box z. Such gear is not shown in Figs. 5 and 6 in order to avoid confusion therein.

With the object of obtaining a good impression from the printing blocks I may arrange a throttle valve on either the admission or exhaust pipe of the cylinder Y working the printing movement, such throttle being operated so as to produce a dwell in the movement while the printing blocks are in contact with the material I. Any suitable means may be provided for automatically operating the throttle valve. A convenient arrangement is shown in Figs. 7, 8, and 9, which as shown comprises a

suitably shaped cam 1 which can be adjusted by means of a handle 2 lengthwise of a lever 3 that is pivotally mounted at 3' on a fixed part of the machine and is operatively connected with the throttle lever 4. The lever and cam are arranged transversely of the path traversed by a roller 5 carried by a bar 6 that is arranged to move in unison with the piston of the printing cylinder, and for that purpose is connected by means of the members 7 and 8 to the tail rod Y^2 attached to that portion. The extent to which the throttle valve is closed will depend upon the position of the adjustable cam 1 on the lever 3.

In a machine as above referred to it is manifest that the material being printed requires to be moved forward at the same time as the tiering or coloring devices move forward, and again requires to be moved forward when the coloring devices move backward. To attain this object in the simplest way, although any convenient method may be employed according to circumstances, I prefer to fit, as shown in Figs. 1, 2 and 3 a rack s on to a tail rod attached to the piston in the tiering cylinder Y so as to drive a spur wheel t of a circumference equal to the travel of the rack so that it makes a complete revolution in one direction or the other as the tiering mechanism moves. This wheel would be mounted on a shaft having a crank u thereon, and this crank would give motion to a shaft carrying the forwarding drums Q which pull forward the endless bands F carrying the material I to be printed by means of a pawl v and ratchet v' . It will be seen that each motion in either direction of the tiering mechanism will give a complete rotation to the crank and, therefore, a complete stroke backward and forward of the crank lever, and that although the crank revolves in a different direction during the forward and backward stroke of the tiering mechanism the resultant movement of the pawl lever is the same.

Having now fully described the nature of my said invention and the best means I know of carrying the same into practical effect, I claim:—

1. In a machine for printing floorcloth, linoleum and the like material as herein described, the combination with a plurality of printing blocks and a corresponding number of tiering devices, of means for raising and lowering the printing blocks, said means comprising a fluid pressure cylinder including a piston rod and actuating mechanism connecting the piston rod and the printing blocks, and of means for traversing the tiering devices, said latter means comprising a second fluid pressure cylinder including a piston rod and motion transmitting connections between the tiering de-

vices and the piston rod of the said second cylinder.

2. In a machine for printing floorcloth, linoleum and the like material as herein described, the combination with a plurality of printing blocks and a corresponding number of tiering devices, of means for raising and lowering the printing blocks, said means comprising a fluid pressure cylinder including a piston rod and actuating mechanism connecting the piston rod and the printing blocks, of means for traversing the tiering devices, said latter means comprising a second fluid pressure cylinder including a piston rod and motion transmitting connections between the tiering devices and the piston rod of the said second cylinder, and means operated by the fluid pressure cylinder that actuates the tiering devices and adapted to forward the material being printed both when the tiering devices move forward and when they move back.

3. In a machine for printing floorcloth, linoleum and the like material as herein described, the combination with a plurality of printing blocks and a corresponding number of tiering devices, of means for raising and lowering the printing blocks, said means comprising a fluid pressure cylinder including a piston rod and actuating mechanism connecting the piston rod and the printing blocks, of means for traversing the tiering devices, said latter means comprising a second fluid pressure cylinder including a piston rod and motion transmitting connections between the tiering devices and the piston rod of the said second cylinder, means operated by the fluid pressure cylinder that actuates the tiering devices and adapted to forward the material being printed both when the tiering devices move forward and when they move back, said latter means comprising a traveling rack carried by the piston rod of the said second cylinder, a rotatably mounted spindle provided with a crank, a spur wheel fixed to said shaft, the wheel meshing with the rack and having a circumference equal in length to the travel of the rack, a pair of rotatably mounted shafts each carrying a drum, an endless band coöperating with the drums and adapted to support the material to be printed, pawl and ratchet mechanism operatively connecting the crank and one of the rotatably mounted drums.

4. In a machine for printing floorcloth, linoleum and the like, the combination of a series of separately functioning devices, a like series of movement transmitting mechanisms operatively connected each with one of said devices, a corresponding number of successively operating fluid pressure cylinders including piston rods, each adapted to actuate one of said mechanisms, a valve on each cylinder and control gear therefor,

Witnesses:
